CLAIM

The ornamental design for a smart helmet, as shown and described.

DESCRIPTION

FIG. 1 is a front perspective view of a smart helmet, showing my new design;

FIG. 2 is a rear perspective view thereof;

FIG. 3 is a front view thereof;

FIG. 4 is a rear view thereof;

FIG. 5 is a side view thereof;

FIG. 6 is another side view thereof;

FIG. 7 is a top view thereof; and,

FIG. 8 is a bottom view thereof.

The broken lines shown in the drawings represent unclaimed portions of the smart helmet and form no part of the claimed design.

The dot-dash broken lines shown in the drawings represent boundaries of the smart helmet and form no part of the claimed design.

1 Claim, 8 Drawing Sheets
